UNITED STATES PATENT OFFICE.

BENGT M. W. HANSON, OF HARTFORD, CONNECTICUT, ASSIGNOR TO PRATT & WHITNEY COMPANY, OF NEW YORK, N. Y., A CORPORATION OF NEW JERSEY.

GRINDING MACHINE.

1,416,462.

Specification of Letters Patent. Patented May 16, 1922.

Application filed July 31, 1918. Serial No. 247,632.

To all whom it may concern:

Be it known that I, BENGT M. W. HANSON, a citizen of the United States, residing at Hartford, in the county of Hartford and 5 State of Connecticut, have invented certain new and useful Improvements in Grinding Machines, of which the following is a specification.

The invention relates especially to grinding machines which are adapted for grinding long cylindrical or approximately cylindrical bodies, such for instance as gun barrels. A machine embodying the invention is provided with a broad faced wheel 10 having a width equal to or exceeding the length of the part of the work to be ground.

One of the objects of the invention is to provide in a machine of the type specified, improved means for supporting the work 15 and for effecting relative movement to bring the work and the wheel into operative engagement. Preferably, as will later more fully appear, the wheel is rotatable about a fixed axis and the work support is movable 20 toward or away from the wheel. In accordance with the invention I provide means whereby the work support may be moved slowly through small distances to effect adjustment and feeding, and I also provide 25 supplemental means whereby the work support may be moved independently of the feed mechanism rapidly through a relatively great distance to remove the work support far enough from the wheel to permit finished work to be removed and new work to 30 be inserted.

Another object of the invention is to provide in a machine having a broad faced grinding wheel, an improved work holding 35 means including a system of back-rests whereby the work may be supported and steadied during grinding at a number of different points.

A further object of the invention is to 40 provide improved means whereby the work may be given a small reciprocatory longitudinal movement during grinding.

A still further object of the invention is 45 to provide, in combination with other features of the machine, an improved guard for the grinding wheel, the guard being bodily movable in an improved manner and being supported in an improved manner.

Another object of the invention is to provide improved means for delivering water 55 to the grinding wheel along the entire width thereof.

Still another object of the invention is to provide in combination with other features of the machine, an improved means for 60 dressing the wheel in conformity with the character and shape of the work to be ground.

Still further objects of the invention will be apparent from the following specification 65 and claims.

In the accompanying drawings I have shown the embodiment of the invention which I now deem preferable, but it will be understood that the drawings are to be considered as merely illustrative and are not to be construed as defining or limiting the scope of the invention, the accompanying 70 claims being relied upon for that purpose.

Of the drawings:

Fig. 1 is a front elevation.

Fig. 2 is a plan view.

Fig. 3 is an end view on an enlarged scale taken from the left, the motor being removed.

Fig. 4 is an end view on the same scale as Fig. 3, taken from the right.

Fig. 5 is a vertical sectional view on the same scale as Figs. 3 and 4 taken along the line 5—5 of Fig. 1.

Fig. 6 is a fragmentary vertical sectional view taken along the line 6—6 of Fig. 3.

Fig. 7 is a fragmentary view similar to the upper right-hand part of Fig. 6 but showing a modified arrangement of parts.

Fig. 8 is an enlarged front view showing the mechanism for swinging the work carrying frame.

Fig. 9 is a fragmentary sectional view taken along the line 9—9 of Fig. 5.

Fig. 10 is a fragmentary sectional view taken along the line 10—10 of Fig. 3.

Fig. 11 is a detail view on an enlarged scale showing two of the back-rests.

Fig. 12 is a fragmentary front view, partly 100 in section, and showing the gearing for operating the wheel dressing device.

Fig. 13 is an end view, partly in section, of the mechanism shown in Fig. 12.

Fig. 14 is a fragmentary sectional view 105 taken along the line 14—14 of Fig. 13.

Fig. 15 is a plan view of a part of the wheel dressing mechanism detached from the other parts of the machine.

Fig. 16 is a front elevation of the mechanism shown in Fig. 15.

Fig. 17 is a detail view of the former.

A machine embodying the invention comprises a main frame 1 upon which is mounted a grinding wheel 2 which is rotatable about a longitudinal horizontal axis. The wheel has a broad working face which preferably extends the full length of the work to be ground. Mechanism is provided for rotating the wheel, this consisting in the present instance of an electric motor 3 mounted on an extension 4 of the main frame. The machine is primarily intended for grinding work which is circular in cross section, but its use is not necessarily limited to the grinding of work of this character. A gun barrel may be taken as an example of the work for which the machine is best adapted. There is provided a suitable work support for holding the work to be ground, which for purposes of illustration will be considered to be a gun barrel such as shown at A. Preferably the work support comprises centers carried respectively, by a headstock 5 and a tailstock 6, which are longitudinally adjustable along horizontal ways formed on a table 7. Means is provided for causing relative approaching and separating movements between the work support and the wheel for initially bringing the work into contact with the wheel and for feeding. In order to provide a rigid support for the wheel which will hold it against vibration, and in order that the wheel may be directly connected with the motor I prefer to mount the wheel in fixed bearings and to move the work support toward and from the wheel. When the wheel is thus mounted the table 7 is carried by a frame 8 which is moved to bring the work into or out of operative engagement with the wheel. Preferably this frame is pivoted near its bottom to the main frame 1, as, for instance, by means of trunnions 9 and 10.

Having now briefly outlined some of the more important elements of the machine, I will now proceed to a more detailed description of the several parts.

As shown most clearly in Fig. 6, there are provided two bearing brackets 11 and 12 which project upward from the main frame 1 and which carry a rotatable spindle 13. Secured to this spindle, by any usual or preferred means and positioned between the bearings, is the aforesaid grinding wheel 2. The motor 3 is mounted with its drive shaft 14 in alinement with the spindle 13, and carried respectively by the spindle 13 and the shaft 14 are flanges 15 and 16. The flanges are provided respectively with oppositely projecting pins 17 and 18 and an

endless flexible belt 19 is laced back and forth over the pins 17 and 18. The mechanism which I have described constitutes a yieldable flexible coupling between the shaft 14 and the spindle 13.

I provide a suitable guard which partly surrounds the grinding wheel. As concerns many of the features of the invention the guard can be of any usual or preferred construction, but I prefer a guard such as is shown in the drawings and will be described.

The guard is constructed in a manner to provide a high tensile strength which will enable it to resist breakage in case of breakage of the grinding wheel. Preferably this tensile strength is provided by forming the sides of the guard of sheet metal. Preferably in order that the guard may be easily opened to permit access to the wheel it is formed with a top section which is readily separable from the bottom section.

As illustrated, the lower section comprises two similar oppositely disposed end plates 20 and 21 positioned adjacent the bearing brackets 11 and 12 respectively. These plates 20 and 21 are connected by rods 22 which extend through suitable apertures in the plates, these apertures being spaced at intervals along the outer edges. Preferably, as shown in Fig. 5, the portions of the rods 22 between the plates are square. A double sheet metal casing 23 is secured to these rods, this casing preferably consisting of a single sheet of metal which extends from the rear and engages the outer surfaces of the several rods and is looped around the front rod. From this front rod the sheet extends rearward engaging the inner surfaces of the rods. The sheet metal is secured to the rods in any suitable manner, as, for instance, by means of rivets 24 extending through apertures in the rods. Preferably the end plates 20 and 21 are provided with grooves, as shown in Fig. 6, into which the edges of the sheet metal 23 extend, thus making a tight joint. Preferably the lower section of the guard is provided with drain apertures as shown at 23^a, 23^b.

The upper section of the guard is constructed similarly to the lower section, this upper section comprising end plates 25 and 26 which are connected by rods 27. Secured to the rods 27 is a sheet metal casing 28 similar to the sheet metal casing 23 already described. The two sections of the guard are separated at their front edges, as shown, to provide access to the wheel, but their rear edges are closely adjacent. Preferably the sheet metal of the two casing sections is extended, as shown at 29 and 30, to overlap and prevent the escape of water between the two sections.

In order that the guard may be moved to accommodate wheels of different diameters and to compensate for changes in the dia- 130

ter of a single wheel due to wear, I provide means whereby both sections of the wheel may be moved backward or forward.

The end plate 20 of the lower section of the guard is provided with apertured ears 31 and 32 which carry a horizontal pin 33. The pin extends through a bearing aperture in the body part of the bearing bracket 11. The opposite end plate 21 is provided with a horizontal lug 34 which fits between lugs 35 carried by the bearing bracket 12 and a latch 36 pivoted to the bearing bracket at 37. As shown in Fig. 3, the length of the pin 33 between the ears 31 and 32 is considerably greater than the width of the bearing bracket 11, thus permitting the pin to slide in the aperture. The construction at the right-hand end also permits forward and backward movement and the entire lower section can thus be adjusted. After adjustment the section can be locked in adjusted position by means of a screw 33^a which engages the screw 33 and by means of a screw 38 which engages the latch 36 and forces it into firm engagement with the lug 34.

The upper section of the guard is preferably supported entirely independently of the lower section. As illustrated extensions 39 and 40 are formed respectively on the bearing brackets 11 and 12. The plates 25 and 26 are provided respectively with lugs 41 and 42 which rest on these extensions and are capable of sliding movement therewith. Each of the lugs is provided with a T-bolt 43 which engages a T-slot 44 in the corresponding extension. By means of these T-bolts the upper section of the guard can be secured in place after adjustment. It will be noted that by removing the nuts on the T-bolts 43 the entire upper section of the guard is loosened so that it can be freely removed to expose the wheel and to permit the wheel with its spindle to be taken out if necessary.

Preferably interlocking means are provided for insuring the uniform movement of the two guard sections forward and backward. As illustrated, this interlocking means comprises projections 45 on the upper plates 25 and 26, these projections extending into grooves 46 in the lower plates 20 and 21.

For convenience in moving the guard forward or backward, there are preferably provided two handles 47. Each of the handles 55 is constructed in two parts formed respectively on the upper and lower plates of the guard.

In order that water may be delivered to the grinding wheel and uniformly distributed along its entire length, I provide a series of nozzles 48 as shown clearly in Figs. 2 and 6. It will be observed that these nozzles are provided with elongated discharge orifices and that the nozzles are placed close together so as to provide a substantially con-

tinuous sheet of water from one end of the wheel to the other. These nozzles are connected, by means of short nipples 49, with a manifold 50 which extends the entire length of the wheel.

If a wheel 2 is to be used which is shorter than the full length for which the machine is designed, one or more of the nozzles 48, at either or both ends, may be removed as indicated in Fig. 7. In this case the corresponding nipples 49 are closed by means of caps 48^a.

The manifold 50 is supported by means of screws 51, 51 which extend respectively through slots 52, 52 formed in brackets 53, 53 carried respectively by the end plates 25 and 26 of the guard. These slots permit the manifold with the nozzles to be moved circumferentially of the wheel. In this way the nozzles can be adjusted in accordance with the diameter of the work being ground. After adjustment the manifold with the nozzles can be clamped in adjusted position by tightening the screws 51, 51 by means of handles 54, 54 secured to the ends thereof.

Inasmuch as the nozzles 48 are carried by the guard, it will be clear that they will be moved forward or backward to accommodate wheels of different diameters when the guard is moved. When the upper section of the guard is taken off to expose the wheel the manifold and the nozzles are carried with it.

Water is supplied to the manifold 50 through two pipes 55 which are connected by means of flexible hose sections 56, 56 with a supply pipe 57. Water may be supplied to the pipe 57 from any desired source, but I prefer to provide a pump which is constructed and connected as a permanent part of the machine. As illustrated, the extension 4 of the main frame which carries the motor 3 is constructed in the form of a tank arranged to receive the water which is discharged from the wheel. For guiding the water into the tank the main frame is provided with edge flanges 58, 58. Positioned in the tank is a pump which is preferably of the centrifugal type. The rotor 59 of the pump is positioned in a casing 60 and is connected with a vertical drive shaft 61 which carries at its upper end a belt pulley 62. A belt pulley 63 is mounted on the motor shaft 14 and a belt 64 passes over and around the two pulleys 62 and 63 to transmit power from the frame to the latter. Suitable idler pulleys 65, 65 are provided for guiding the belt. The discharge side of the pump is connected by means of a pipe 66 with the aforesaid supply pipe 57. By means of this construction water may be supplied under proper pressure to the manifold 50 and to the nozzles whenever the machine is in operation.

As already stated, the machine is provided with a swinging frame 8 which carries the

70

75

80

90

95

100

105

110

115

120

125

130

work. The frame is provided at its ends with two large depending lugs 67 and 68 which carry respectively the aforesaid trunnions 9 and 10. These trunnions are seated 5 in suitable bearing apertures in the main frame. The swinging frame 8 is preferably of skeleton construction, having a thin front plate 68^a which joins near its top with a horizontal plate 68^b. A plate or apron 68^c 10 extends diagonally downward from the inner edge of the plate 68^b and overlaps the front flange 58 on the main frame, as clearly shown in Fig. 5. This apron assists in preventing the escape of water and serves to 15 guide it downward into the space between the flanges 58. The table 7 is supported above the plate 68^b and between the table and the plate there is provided a long clear open space for a purpose which will present 20 only appear.

The table 7 is provided with longitudinal ways 69 and 70 and a longitudinal T-slot 71. The headstock 5 is slidably mounted on the ways 69 and 70 and is adapted to be held in 25 place and clamped by means of a bolt 72 entering the T-slot 71. As shown most clearly in Fig. 10, the body of the headstock carries a longitudinal bushing 73 which is fixed against relative movement. Mounted 30 in the bushing 73 is a sleeve 74 which carries a center 75 adapted to engage and support one end of the work. The sleeve 74 is preferably longitudinally slidable and is held against rotative movement by means of a 35 pin 76 which enters a slot 77 in the bushing 73. The wall of the body part of the headstock is provided with an aperture through which the pin 76 may be put in place or removed, this aperture being normally closed 40 by a plug 78. For a purpose which will presently appear, a spring-pressed plunger 79 is mounted in a longitudinal recess in the bushing 73 and bears against the pin 76, thus tending to hold the sleeve 74 in its rearmost 45 position.

The headstock is provided with power operated means for rotating the work. Preferably this comprises a gear 80 rotatably mounted on the bushing 73. The hub 50 of the gear is extended toward the right and is provided with an annular groove into which fits a shoe 81 serving to hold the gear in place. The hub of the gear is also extended toward the left and carries a pin 82 55 adapted to engage a dog B secured to the work A. The gear 80 meshes with an idler gear 83 carried by a stud 84 and the gear 83 in turn meshes with a pinion 85 mounted on a rotatable sleeve 86. Preferably a plate 87 60 is provided for covering the several gears. The sleeve 86 is rotatable in a suitable bearing aperture in the body of the headstock and is splined to a longitudinal shaft 88. Mounted on the end of the table 7 is a housing 89 carrying a bushing 90 having its axis 65

in alinement with the axis of the shaft 88. Rotatably mounted within the bushing 90 is a sleeve 91 which has splined engagement with the said shaft. The sleeve 91 carries at its outer end a belt pulley 92 and a similar 70 belt pulley 93 is loosely mounted on the projecting end of the bushing 90. It will be clear that when the pulley 92 is rotated power will be transmitted through the shaft 88 and the several gears to rotate the work 75 A by means of the dog B and the pin 82. The splined engagement of the shaft 88 with the sleeves 86 and 91 permits the headstock to be moved longitudinally along the table without interfering with the power connection. 80

The trunnion 9 is preferably extended toward the left and has rotatably mounted upon it two belt pulleys 94 and 95 which are rigidly connected together. The belt pulley 95 is wide and is in register with the two belt pulleys 92 and 93. A belt 96 passes over these pulleys and is adapted to be shifted from one to the other by means of a belt shifter 97 operated by a lever 98. A 90 belt pulley 99 is mounted on the spindle 13 in register with the belt pulley 94 and a belt 100 passes over these two pulleys. By means of the two belts 96 and 100 power is transmitted to drive the headstock, and, inasmuch as the pulleys 94 and 95 are mounted with their axes coincident with the pivotal axis of the swinging frame, it will be clear that the transmission of power is not interfered with by movements of the frame. 100

The tailstock 6 is slideable along the aforesaid ways 69 and 70 on the table and the tailstock can be clamped in adjusted position by means of a bolt 101 which enters the T-slot 71. Carried by the body of the 105 tailstock is a sliding sleeve 102 which carries a center 103 in alinement with the center 75. The outer end of the sleeve 102 is recessed to receive a spring 104 which normally tends to move the sleeve toward the 110 headstock. For moving the sleeve in the opposite direction there is provided a lever 105 pivoted at 106 and provided with a finger 107 which engages the walls of an aperture in the sleeve. Preferably a screw 108 is 115 threaded into the sleeve and is provided with a knob 109. This screw is used for ejecting the center 103 when necessary.

The machine is primarily intended for use in grinding a large number of pieces of 120 the same character and size and when it is to be so used the headstock and the tailstock are first adjusted to the proper distance apart. The work to be ground is first dogged and then the dogged end is placed in engagement with the center 75. By means of the lever 105 the operator draws back the center 103 against the pressure of the spring 104. The work is then swung into alinement with the centers and the center 103 is 125 130

permitted to move under the action of the spring into engagement with the work. In this way the work is engaged by the centers with predetermined pressure.

- 5 From the description that has already been given it will be understood that in the preferred embodiment of the invention the wheel is fixed against bodily movement and that the work is moved by means of the 10 swinging frame into and out of engagement with the wheel. For swinging the frame to effect feeding I provide a draw bolt or screw 110 which extends through an aperture in the front of the frame. This screw engages 15 a threaded nut 111 carrying a hand wheel 112. The inner end of the screw is horizontally pivoted to a bracket 113 carried by the main frame and projecting into the space between the plate 68 and the apron 20 68° of the swinging frame. The apron serves to prevent water from reaching the pivot for the screw. Surrounding the nut 111 is a sleeve 114 which is supported by pivot studs 115 extending inward from opposite sides of the aperture in the swinging 25 frame. Suitable means is provided for connecting the threaded nut 111 and the hand wheel 112 with the swinging frame so that rotative movement of the wheel will serve to 30 move the frame forward or backward on its pivotal axis as required. The operator, by turning the hand wheel 112, can change the position of the frame as required to move the work into or out of engagement with the 35 grinding wheel and to feed the work during the grinding operation. Preferably, in order that the amount of feed may be accurately observed, there is provided a ring 121 which has frictional engagement with 40 an annular flange on the hand wheel. The ring 121 carries a pointer 122 which cooperates with a scale 123 on the periphery of the wheel. The ring 121 also carries a finger 124 which is adapted to engage a stop 125 45 which projects outward from the swinging frame. In practice, the operator turns the hand wheel in the clockwise direction until the work is brought into contact with the wheel and is reduced to the required size. 50 In turning, the finger 124 comes into contact with the stop 125 and thereafter the ring 121 slips on the flange of the hand wheel and remains stationary. When grinding is completed the wheel is turned in the counter-clockwise direction to remove the work from 55 contact with the wheel and the finished work is removed. When a new piece is put in place to be ground the operator again turns the hand wheel in the clockwise direction until the finger 124 again engages the stop 125. The engagement of the finger with the stop constitutes notice to the operator that the work is ground approximately to the required size. If it is found 60 that because of wear of the wheel or for 65

some other reason further grinding is required, this can be effected by still further turning the hand wheel, the amount of turning being measured by the graduations of the scale 123.

As already stated, the grinding wheel 2 extends substantially the entire length of the work or over that part of the work which is to be ground, and for this reason it is difficult for the operator to remove the finished work and put a new piece in place when the work is close to the wheel. There is danger that the operator will accidentally engage the work with the wheel in putting it in or taking it out and thus mar it, 70 and there is further danger that he will allow his hands to contact with the wheel, thus seriously injuring himself. In order to avoid these difficulties, I have provided means whereby the swinging frame may be 75 moved quickly through a considerable angle to remove the axis of the centers from the wheel a distance sufficient to enable the operator to put the work in place and remove it with entire safety.

With this end in view the connection between the nut 111 and the sleeve 114 preferably comprises means whereby relative movement may be effected without turning the nut. In the preferred embodiment of 95 the invention, I provide a cam collar 116 which is rotatably and relatively slidably mounted on the sleeve 114 and which is provided with a handle 117 by means of which it may be turned. The collar 116 at its 100 outer end is associated with the hand wheel 112, a ball bearing 118 preferably being interposed. At its inner end the collar 116 is provided with two oppositely positioned similarly formed cam surfaces 119. These 105 two surfaces respectively engage rollers 120 carried by the aforesaid studs 115. When the cam collar 116 is in the position shown in Figs. 5 and 8 the highest points of the cam surfaces are in engagement with the 110 rollers, and in this way the swinging frame is supported in its normal operative position. By moving the handle 117 to the position indicated by dotted lines in Fig. 8, the rollers will be made to travel relatively 115 downward along the cam surfaces 119, thus permitting the frame to swing outward and separate the axis of the centers from the wheel. It will be noted that the hub of the hand wheel is recessed to permit the outer 120 end of the sleeve 114 to travel outward without interference when the cam collar 116 is turned. After the finished work has been taken out and a new piece put in, the handle 117 is returned to the position shown 125 by full lines in Fig. 8, thus restoring the table to exactly its former position. Preferably, as shown in Figs. 3, 8 and 9, the cam collar 116 carries a stop 126 which serves to accurately limit the movement of the 130

collar and of the handle in the clockwise direction.

By preference the aforesaid stop 125 is not rigidly secured to the swinging frame but is pivotally mounted by means of a pivot pin 127. This pivot pin carries a crank arm 128 having a finger 129. The finger 129 engages a cam surface 130 formed on the cam collar 116. The cam surface 130 is so shaped that it engages the finger 129 and turns the pin 127 to swing the stop 125 upward whenever the collar 116 is turned to swing the frame backward. Thus when the table is moved to its outer position the stop 125 is automatically swung upward out of the path of the finger 124. This permits the hand wheel 112 to be turned indefinitely in either direction for additional movement of the swinging frame without disturbing 15 in any way the adjustment of the friction ring 121 and of the finger 124 carried thereby. When the collar 116 is turned to swing the frame forward the stop 125 may be returned to operative position.

Preferably, in order to partly counter-balance the weight of the swinging frame and of the parts attached thereto, I provide two links 131 which are pivoted to the swinging frame at their front ends and which are engaged at their rear ends by coil springs 132. These springs serve to tension the links and to apply to the frame a force tending to swing it upward and rearward. This construction enables the operator to more easily 35 swing the frame by means of the handle 117.

Preferably the table 7 is not fixedly connected to the swinging frame but is adjustably connected thereto so as to be capable of a slight pivotal movement about a pivot pin 40 133 shown by dotted lines in Fig. 1. For swinging the table about this pivot there is provided a screw 134 threaded into a nut 135 which is held against rotation and which has a tongue-and-groove engagement with a 45 bracket 136 carried by the swinging frame. The screw extends through a bearing aperture in a bracket 137 carried by the table and is held against longitudinal movement with respect to the bracket. The screw carries a 50 knob at 138 for turning it. By turning the screw 134 the table can be swung slightly in either direction to properly position the axis of the centers in parallelism with the axis of the grinding wheel; or, if required for tapered work, to position the axis of the 55 centers at a slight angle to the axis of the wheel. Preferably the hub of the knob 138 is provided with graduations at 139 to indicate the amount of turning of the screw and thus indicate the amount of adjustment of the table. After adjustment, the table can be clamped in place by means of bolts 140 and 141.

It sometimes happens that the surface of 60 the grinding wheel is not entirely even and has

small circumferential depressions or grooves. When such depressions are present they tend to cause corresponding ridges on the work and thus diminish the accuracy of the finished product. To avoid such inaccuracies 70 I preferably provide means whereby the work may be moved a short distance longitudinally during grinding. As shown in Fig. 10, a transverse rotatable shaft 142 is mounted in a suitable aperture in the body 75 of the headstock. This rock shaft is provided at its forward upper end with a hand wheel 143 and at its lower end it is provided with a cam or eccentric 144. Threaded into the outer end of the sleeve 74 is a screw 80 145 carrying a lock nut 146. The end of this screw is positioned adjacent the cam 144. The operator, by turning the hand wheel 143, can turn the cam 144 and thus move the sleeve 74 toward the tailstock, overcoming 85 the resistance of the spring plunger 79. The movement of the sleeve effects the movement of the work in the same direction, the tailstock center 103 yielding against the action of the spring 104 to permit such movement. 90 As soon as movement of the cam 144 permits, the work is moved in the opposite direction under the action of the spring 104. By this means the operator can slowly reciprocate the work longitudinally, thus entirely avoiding the possibility of ridges or 95 irregularities thereon.

I provide suitable means in the form of back-rests for supporting the work during grinding. Preferably there are several 100 back-rests positioned at regular intervals along the work. In the preferred embodiment of the invention I construct the back-rests in pairs so that two of them can be put in place or removed at the same time. As 105 illustrated, particularly in Figs. 5 and 11, I provide a body casting 147 for each pair of rests. This body is adapted to slidably engage the upper way 69 on the table and can be secured in place by means of a bolt 148 110 having an enlarged head 149 adapted to engage the lower edge of the way. The body casting 147 is provided with a central bearing bracket 150 in which is supported a pivot pin 151 extending longitudinally of the machine. Mounted on the pivot pin 151 at each side of the bearing bracket 150 is a lever 152. Each lever 152 carries at its lower end two shoes 153 and 154 which are arranged to engage the work at the side and 115 at the bottom respectively. Adjacent the rear end of each lever 152 the body casting 147 is provided with an apertured boss 155. Fitted in the aperture of this boss are bearing bushings 156 and 157 positioned respectively at the upper and lower ends. Slidably extending through these bushings is a rod 158 which has a relatively loose pivotal connection at its rear upper end with the forward upper end of the lever 152. The 120 125 130

rod 158 carries a collar 159 which is positioned between the bushings and a coil spring 160 surrounds the rod, abutting at one end against the collar 159 and at the 5 other end against the end of the bushing 156. The spring 160 tends to move the rod outward and thus tends to swing the lever 152 to press the shoes 153 and 154 against the work. The bushing 157 is adjusted to engage the collar 159 and serve as a stop to limit the movement. The bushing 156 can be adjusted to regulate the pressure of the 10 spring.

Fig. 2 shows several pairs of back-rests in place, these being spaced at proper intervals along the work. It will be understood that when the work varies in diameter each back-rest may be adjusted to properly engage and support the work at its own particular point. 15 This is done by adjusting the bushing 157 to provide a stop when the work is reduced to the proper size, and by adjusting the bushing 156 to provide the proper spring pressure.

In order that the finished work may be easily removed and new work put in place, it is desirable to provide means whereby the several back-rests may be easily and quickly withdrawn. For this purpose I mount on 20 the table 7 a longitudinal eccentric rock shaft 161. This shaft carries at its ends trunnions 162 which are mounted in bearings 163 carried by the table. At the end of one of the trunnions is a handle 164 by 25 means of which the rock shaft can be turned. It will be clear that when the eccentric rock shaft is in the position shown in Fig. 5 the several back-rests will be permitted to engage the work. However, when the handle 40 164 is turned through approximately 180° the surface of the eccentric rock shaft 161 will engage the lower forward ends of all of the rods 158 and will force them rearward and upward, thus removing the shoes 153 and 45 154 from engagement with the work.

The surface of the grinding wheel 2 must conform to the shape of the work to be ground. For cylindrical or uniformly tapered work the wheel is preferably cylindrical throughout. For work other than straight tapered work which varies in diameter the wheel must be dressed to a contour corresponding to the contour of the work. In order that the dressing of the wheel, 50 whether for cylindrical grinding or for contour grinding, may be easily and accurately effected, I provide a special wheel dressing mechanism which constitutes a permanent part of the machine. The wheel dressing mechanism by itself is not claimed as a 55 part of this invention, being covered by my copending application for wheel dressing mechanism, Serial No. 247,637 filed on even date herewith. This copending application 60 shows a construction which is in many re-

spects similar but which is different in details.

Formed in the bottom of the table 7 is a longitudinal dovetailed recess which forms a guideway. Fitted in this recess for sliding movement is a slide 165. The slide 165 carries a wheel dressing tool 167 of any usual or preferred construction. The slide 165 is adapted to be moved longitudinally of the table in the space between the bottom 75 of the table and the top of the plate 68^b. When it is so moved the tool 167 travels along the surface of the wheel to properly dress and true it. In order that the wheel may be dressed to any desired contour the 80 tool 167 is not carried directly by the slide 165 but by a second slide 166 which is transversely movable with respect to the slide 165. I provide means whereby the slide 166 may be moved forward or backward simultaneously with the longitudinal movement to enable the tool to dress the wheel to the required contour. This means comprises a former plate or bar 168 (shown in detail in 85 Fig. 17) which is secured in a rabbet formed at the lower front edge of the table. The front edge of the former is shaped to conform to the required contour of the wheel and it will be understood that the former 168 can be removed and another former substituted having a different contour. The 90 slide 166 is provided with means for engaging the former 168, this means preferably comprising a bracket 169 projecting upward from the front end of the slide and a roller 100 170 carried by the bracket. A coil spring 171 is provided for pressing the slide forward and holding the roller in engagement with the former 168. Preferably there is a 105 cover secured to the table and extending over the former and the roller to protect them and exclude dirt. As shown the aforesaid bracket 137 is formed to constitute this cover.

For moving the slide 165 longitudinally 110 of the table, I preferably provide a longitudinal threaded shaft or screw 173 which is mounted at its ends in suitable bearings in the table. This screw extends through an aperture in the slide 165 and has threaded 115 engagement therewith. It will be seen that when the screw is turned the slide will be moved longitudinally, carrying with it the slide 166 which is at the same time moved forward or backward under the control of the former 168. I prefer to provide power mechanism for rotating the threaded shaft or screw 173. When such a power mechanism is provided a suitable housing 174 is secured to the table at the right-hand end 120 and the shaft 173 is extended into the housing. Rotatably mounted on the shaft within the housing are two gears 175 and 176. Splined to the shaft between the gears is a 125 clutch collar 177. This collar has teeth at 130

one side adapted to engage pins carried by the gear 175 and has teeth at the other side adapted to engage pins carried by the gear 176. Rotatably mounted in the housing 174 5 is a shaft 178 carrying a belt pulley 179 at the right-hand end. The shaft 178 carries a pinion 180 which meshes with the aforesaid gear 176. The shaft 178 also carries a gear 181 which meshes with an idler gear 10 182, the idler gear in turn meshing with the aforesaid gear 175.

Rotatably mounted in the aforesaid trunnions 9 and 10 is a shaft 183 connected at its left-hand end to the aforesaid pulleys 94 15 and 95. At its right-hand end the shaft carries a belt pulley 184. A belt 185 passes over the pulleys 184 and 179. By means of the mechanism described power is transmitted from the rotatable pulleys 94 and 95 20 to rotate the two gears 175 and 176. The gear 176 is rotated slowly in one direction and the gear 175 is rotated rapidly in the other direction.

For operating the clutch collar 177 there 25 is provided a forked lever 186 mounted on a vertical pin 187 supported in bearings in the housing 174. This lever 186 carries projections which are seated in the annular groove of the collar and when the lever is 30 turned the collar is moved to the right or to the left into engagement either with the gear 176 or with the gear 175. As shown in Fig. 14, the lever 186 carries a spring-pressed plunger 188 adapted to cooperate 35 with a notched abutment 189. When the plunger is seated in the notch, as illustrated, the clutch collar is held in its central neutral position. When the plunger engages either 40 of the side surfaces of the abutment the spring tends to assist in moving the lever to carry the clutch collar into full engagement with one or the other of the gears. Connected with the pin 187 is a lever 190 which extends forward. To this lever 190 45 there is pivoted a rod 191 which extends across the front of the machine and is supported by bearings 192 and 193. Carried by the rod 191 are handles 194, 194 by means of which the rod can be moved longitudinally 50 to shift the clutch. When the clutch is engaged with the gear 176 the screw 173 is rotated slowly in the direction to move the dressing tool from left to right across the wheel. When the clutch is shifted to 55 engage the gear 175 the dressing tool is moved rapidly in the opposite direction. Preferably the rod 191 is provided with collars 195, 195 which are permanently secured in place and are adapted to be engaged by the slide 166 to automatically shift the rod and prevent the movement of the slide beyond a certain limit in either direction. Preferably there are also provided 60 collars 196, 196 which are adjustably secured to the shaft 191. These collars are adapted

to be engaged by a latch 197 carried by the slide 166 and adapted to be swung when desired to clear the collars 196. It will be seen that the collars 196 can be adjusted to automatically stop the tool slide in a 70 predetermined position after movement in either direction. If for any reason further movement is desired, this can be started by lifting the latch 197 and shifting the rod 191 manually. The fixed collars 195 serve 75 to prevent movement of the slide so far as to injure the machine in any way.

As will be apparent from the foregoing description, the machine is primarily intended for the grinding of a large number 80 of similar pieces of work. In the preliminary adapting and adjusting of the machine for the work to be done, it is first necessary to construct a former 168 having its effective edge shaped to conform to the 85 required contour of the finished work. When such a former has been constructed it is put in place in the machine and is used for dressing the grinding wheel. Before starting the dressing operation the operator 90 preferably adjusts the two collars 196, 196 to limit the movement of the dressing mechanism at positions at or near the edges of the wheel. Assuming that the slide 165 is in its left-hand position, the operator, by 95 means of the hand wheel 112, swings the frame 8 far enough to bring the tool 167 into engagement with the wheel. Then the operator, by means of the rod 191, starts the movement of the slide 165 which carries the tool 167 slowly toward the right. During this movement the position of the tool 167 is controlled by the former 168, and, because of the spring 171, the pressure of the tool against the wheel is 100 definitely limited. After movement across the wheel the slide is automatically stopped by the right-hand collar 196. In initially dressing the wheel it may be necessary to move the tool across it several times. When 110 this is required the operator moves the hand wheel slightly to withdraw the tool from engagement with the wheel and then, by means of the rod 191, shifts the clutch to move the slide 165 rapidly toward the left. The slide is automatically stopped by the 115 left-hand collar 196. Then the tool can be moved toward the right as before, and this operation can be repeated until the wheel has assumed a contour corresponding exactly to that of the former 168.

The headstock and the tailstock are properly positioned on the work support or table to engage and hold the work blanks. Before putting the blank in place the operator, by 125 means of the lever 117, swings the work support forward. The blank is first fitted with a dog and then is engaged with the headstock center 75 and the tailstock center 103 is drawn backward and afterward released 130

into engagement with the end of the blank.

The several back-rests are properly positioned to engage the blank at suitable intervals along its length and each of the back-rests is adjusted to apply the required spring pressure to the work. While the work support is being put in place the back-rests are held inoperative by means of the eccentric shaft 161. After the blank is properly engaged by the centers the eccentric shaft 161 is turned to permit the shoes to engage the blank.

After the blank has been thus put in place and engaged, the operator turns the lever 117 to its right-hand position and thus swings the work support forward. Further forward movement of the work support is effected by turning the hand wheel 112 in the clockwise direction. As the hand wheel 20 is turned the lug 124 engages the stop 125 and during further movement of the hand wheel the ring 121 slips on its bearing. The hand wheel is turned until the work is reduced to size.

25 During the grinding operation the operator may, if he finds it necessary, reciprocate the work to a slight extent longitudinally by means of the hand wheel 142. In the case of cylindrical work this longitudinal reciprocation may take place without restriction. However, in the case of shouldered work such as illustrated, the blank must be carefully moved in the direction to carry the shoulder of the blank away from the corresponding shoulder of the wheel.

As soon as the work has been reduced to size the operator turns the lever 117 toward the left, thus swinging the work support forward. This forward movement of the work support carries the blank far enough away from the wheel to permit its easy removal and to permit the easy substitution of an unground blank.

After an unground blank has been put in place the handle 117 is again turned toward the right, the operator first, however, having given the hand wheel 112 a part of a turn in the counter-clockwise direction. In effecting grinding of the second blank, the operator 50 again turns the hand wheel in the clockwise direction until the lug 124 again engages the stop 125. This engagement constitutes notice to the operator that the work is ground to size or approximately to size.

55 As the wheel wears and becomes reduced in diameter the guard may be moved backward correspondingly. When it becomes necessary to inspect the wheel this can be readily done by removing the drop section 60 of the guard. It will be noted that inasmuch as the nozzles 48 are mounted on the guard they will be moved backward when the guard is moved backward and will also be removed when the top section of the guard 65 is removed.

What I claim is:

1. In a grinding machine, the combination of a main frame, a grinding wheel mounted on the frame for rotation about a fixed axis, flanges at the edges of the main frame 70 for preventing the escape of water, an auxiliary frame pivoted to the main frame for movement about an axis parallel with the wheel axis and below the level thereof, a work support on the auxiliary frame adapted to hold a work blank in operative relation to the wheel at approximately the level of the wheel axis, and an apron carried by the auxiliary frame and extending downward and rearward over the adjacent flange 75 on the main frame.

2. In a grinding machine, the combination of a main frame, a grinding wheel mounted on the frame for rotation about a fixed axis, an auxiliary frame pivoted to the main frame 80 for movement about an axis parallel with the wheel axis and below the level thereof, a work support on the auxiliary frame adapted to hold a work blank in operative relation to the wheel at approximately the level of the 85 wheel axis, means for moving the auxiliary frame about its pivot comprising a draw bolt pivoted to the main frame and extending through an aperture in the auxiliary frame, and an apron carried by the auxiliary frame 90 and extending downward and rearward over the pivotal connection between the main frame and the draw bolt.

3. In a grinding machine, the combination of a rotatable grinding wheel, a work support for holding a work blank in operative relation to the wheel, feed mechanism for effecting a relative approaching or separating movement between the wheel and the work support, and means for causing a supplemental approaching or separating movement without disturbing the adjustment of the feed mechanism.

4. In a grinding machine, the combination of a rotatable grinding wheel, a work support for holding a work blank in operative relation to the wheel, feed mechanism for effecting a relative approaching or separating movement between the wheel and the work support, and means operable independently of the feed mechanism for causing a separating movement away from the relative positions determined by the feed mechanism and for causing an approaching movement exactly to the said relative positions.

5. In a grinding machine, the combination of a grinding wheel rotatable about a fixed axis, a work support for holding a work blank in operative relation to the wheel, feed mechanism for moving the work support toward or from the wheel, and means for supplementally moving the work support toward or from the wheel without disturbing the adjustment of the feed mechanism.

6. In a grinding machine, the combina- 130

tion of a grinding wheel rotatable about a fixed axis, a work support movable about a pivotal axis parallel with the wheel axis and adapted to hold a work blank in operative relation to the wheel, feed mechanism for moving the work support about its pivotal axis toward or from the wheel, and means for supplementally moving the work support about its pivotal axis toward or from the wheel without disturbing the adjustment of the feed mechanism.

7. In a grinding machine, the combination of a grinding wheel rotatable about a fixed axis, a work support movable about a pivotal axis parallel with the wheel axis and provided with devices for holding a work blank and rotating it about an axis parallel with the wheel axis, feed mechanism for moving the work support about its pivotal axis toward or from the wheel without disturbing the adjustment of the feed mechanism.

8. In a grinding machine, the combination of a grinding wheel rotatable about a fixed axis, a work support movable toward and from the wheel and adapted to hold a work blank in operative relation to the wheel, feed mechanism for moving the work support, and mechanism interposed between the feed mechanism and the work support for transmitting the action of the feed mechanism, the said interposed mechanism being adjustable independently of the feed mechanism to move the work support.

9. In a grinding machine, the combination of a grinding wheel rotatable about a fixed axis, a work support movable toward and from the wheel and adapted to hold a work blank in operative relation to the wheel, feed mechanism for moving the work support, mechanism including a pivoted cam interposed between the feed mechanism and the work support for transmitting the action of the feed mechanism, and means for adjusting the cam independently of the feed mechanism to move the work support.

10. In a grinding machine, the combination of a main frame, a grinding wheel mounted on the main frame for rotation about a fixed axis, a work support movable toward and from the wheel and adapted to hold a work blank in operative relation to the wheel, a draw bolt connected to the main frame, feed mechanism engaging the draw bolt for moving the work support, mechanism interposed between the feed mechanism and the work support for transmitting the action of the feed mechanism, and means for moving the said interposed mechanism to move the work support independently of the feed mechanism.

11. In a grinding machine, the combina-

tion of a main frame, a grinding wheel 65 mounted on the main frame for rotation about a fixed axis, a work support movable toward and from the wheel and adapted to hold a work blank in operative relation to the wheel, a draw bolt connected to the main 70 frame, feed mechanism engaging the draw bolt for moving the work support, a cam mounted on the draw bolt between the feed mechanism and the work support for transmitting the action of the feed mechanism, 75 and means for turning the cam to move the work support independently of the feed mechanism.

12. In a grinding machine, the combination of a main frame, a grinding wheel 80 mounted on the main frame for rotation about a fixed axis, a work support movable toward and from the wheel and adapted to hold a work blank in operative relation to the wheel, a draw bolt connected to the main 85 frame, feed mechanism comprising a hand wheel engaging the draw bolt for moving the work support, an arm frictionally connected with the hand wheel, a stop for limiting the movement of the arm, mechanism interposed between the feed mechanism and the work support for transmitting the action of the feed mechanism, and means for moving the said interposed mechanism to move the work support independently of the feed mechanism and without moving the arm with respect to the hand wheel. 95

13. In a grinding machine, the combination of a main frame, a grinding wheel mounted on the main frame for rotation 100 about a fixed axis, a work support movable toward and from the wheel and adapted to hold a work blank in operative relation to the wheel, a draw bolt connected to the main frame, feed mechanism comprising a hand wheel engaging the draw bolt for moving the work support, an arm frictionally connected with the hand wheel, a stop normally positioned to limit the movement of the arm but movable out of the path of the arm 105 to permit the movement thereof indefinitely in either direction, mechanism interposed between the feed mechanism and the work support for transmitting the action of the feed mechanism, and means for moving the said interposed mechanism to move the work support independently of the feed mechanism and without moving the arm with respect to the hand wheel. 110

14. In a grinding machine, the combination of a grinding wheel rotatable about a fixed axis, a work support movable toward and from the wheel and adapted to hold a work blank in operative relation to the wheel, feed mechanism comprising a hand wheel for moving the work support, an arm frictionally connected with the hand wheel, a stop normally positioned to limit the 115 120 125

- movement of the arm, mechanism interposed between the feed mechanism and the work support for transmitting the action of the feed mechanism, means for moving the said 5 interposed mechanism to move the work support independently of the feed mechanism and without moving the arm with respect to the hand wheel, and means for moving the stop to an inoperative position upon 10 the movement of the work support away from the wheel by the said interposed mechanism.
15. In a grinding machine, the combination of a main frame, a grinding wheel mounted on the main frame for rotation 15 about a fixed axis, a work support movable toward and from the wheel and adapted to hold a work blank in operative relation to the wheel, a draw bolt connected to the main frame, feed mechanism comprising a hand wheel engaging the draw bolt for moving the work support, an arm frictionally connected with the hand wheel, a stop normally positioned to limit the movement of the arm, 20 a cam mounted on the draw bolt between the feed mechanism and the work support for transmitting the action of the feed mechanism, means for turning the cam to move the work support independently of the feed 25 mechanism and without moving the arm with respect to the hand wheel, and means for moving the stop to an inoperative position upon the turning of the cam to move the work support away from the wheel.
- 30 35. 16. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, and means for causing a supplemental 40 approaching or receding movement without disturbing the adjustment of the feed mechanism.
- 45 50. 17. The combination in a cylindrical grinding machine, of a work support movable about a horizontal pivotal axis and provided with devices for holding a work blank and rotating it about an axis parallel to the pivotal axis, a rotatable grinding wheel having its axis parallel with the aforesaid axes and having a broad face extending the full length of the part of the blank to be ground, feed mechanism for moving the work support about its pivotal axis toward or from 55 the wheel, and means for causing a supplemental movement of the work support toward or from the wheel without disturbing the adjustment of the feed mechanism.
- 60 65. 18. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, and a plurality of back-rests carried by the work support and engaging the work at 70 intervals along its length.
- 75 80. 19. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, and a plurality of back-rests carried by the work support and engaging the work, some of the back-rests being bodily movable 85 independently of others whereby their distribution along the work may be changed.
- 90 95. 20. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, and a plurality of back-rests carried by the work support and engaging the work, 100 the back-rests being connected in pairs and each pair being bodily movable independently of the other pairs whereby the distribution along the work may be changed.
- 105 110. 21. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, and a plurality of independently acting and independently adjustable back-rests carried by 115 the work support and engaging the work at 120 intervals along its length.
125. 22. The combination in a cylindrical grinding machine, of a work support provided with devices for holding and rotating a work blank, a rotatable grinding wheel having its axis parallel with the axis of the work blank and having a broad face extending the full

- length of the part of the blank to be ground, feed mechanism for effecting a relative approaching or separating movement between the wheel and the work support, a plurality 5 of back-rests carried by the work support and engaging the work at intervals along its length, and means for simultaneously withdrawing all of the back-rests from engagement with the work.
- 10 23. The combination in a cylindrical grinding machine, of a work support provided with devices for holding and rotating a work blank, a rotatable grinding wheel having its axis parallel with the axis of the work blank and having a broad face extending the full length of the part of the blank to be ground, feed mechanism for effecting a relative approaching or separating movement between the wheel and the work support, a plurality of back-rests carried by the work support and engaging the work at intervals along its length, and means comprising a longitudinally extending eccentric shaft for simultaneously withdrawing all of 20 the back-rests from engagement with the work.
- 25 24. In combination, a grinding wheel rotatable about a fixed axis, a table movable toward and from the wheel and provided with longitudinal ways, a headstock and a tailstock longitudinally adjustable along the ways on the table, mechanism carried by the headstock for rotating a work blank, a longitudinal shaft having splined engagement with the said mechanism, and driving mechanism for the shaft mounted on the end of the table and fixed against longitudinal movement.
- 30 25. In combination in a grinding machine, a main frame, a work support provided with devices for holding a work blank, an auxiliary frame carrying the work support and movable with respect to the main frame about an axis parallel to the axis of the blank, power actuated means movable with the auxiliary frame for rotating the blank, a grinding wheel rotatable about a fixed axis parallel with the axis of the work blank and having a broad face extending the full 35 length of the part of the blank to be ground, feed mechanism for moving the auxiliary frame about its pivotal axis toward or from the wheel, and means whereby the blank may be longitudinally reciprocated to a slight extent during grinding independently of the auxiliary frame and without interfering with the application of power for rotative movement.
- 40 26. In combination in a grinding machine, a main frame, a work support provided with devices for holding a work blank, an auxiliary frame carrying the work support and movable with respect to the main frame about an axis parallel to the axis of the blank, power actuated means movable with the auxiliary frame for rotating the blank, a grinding wheel rotatable about a fixed axis parallel with the axis of the work blank and having a broad face extending the full 45 length of the part of the blank to be ground, feed mechanism for moving the auxiliary frame about its pivotal axis toward or from the wheel, and means whereby the blank may be longitudinally reciprocated to a slight extent during grinding independently of the auxiliary frame and without interfering with the application of power for rotative movement.
- 50 27. In combination in a cylindrical grinding machine, a rotatable grinding wheel, a work support provided with alined centers for holding a work blank in operative relation to the wheel, means for rotating the work on the centers, feed mechanism for effecting a relative approaching or separating movement between the wheel and the work support, and means for moving the centers longitudinally independently of other parts of the work support in order to reciprocate the blank to a slight extent during 55 grinding.
28. In combination in a cylindrical grinding machine, a rotatable grinding wheel, a work support provided with alined centers for holding a work blank in operative relation to the wheel, means for rotating the work on the centers, feed mechanism for effecting a relative approaching or separating movement between the wheel and the work support, means operable during grinding for reciprocating one of the centers longitudinally to a slight extent independently of other parts of the work support, and a spring for pressing the other center against the blank and causing it to partake of the reciprocatory movement.
29. In combination in a cylindrical grinding machine, a rotatable grinding wheel, a work support provided with alined centers for holding a work blank in operative relation to the wheel, means for rotating the work on the centers, feed mechanism for effecting a relative approaching or separating movement between the wheel and the work support, a spring for pressing one of the centers against the blank, and a device operable during grinding for moving the other center longitudinally in one direction in opposition to the spring independently of other parts of the work support, the blank and the centers being returned by the spring independently of the said device.
30. In combination in a cylindrical grinding machine, a rotatable grinding wheel, a work support provided with alined centers for holding a work blank in operative relation to the wheel, means for rotating the work on the centers, feed mechanism for effecting a relative approaching or separating movement between the wheel and the work support, a spring for pressing one of the centers against the blank, and a device operable during grinding for moving the other center longitudinally in one direction in opposition to the spring independently of other parts of the work support, the blank and the centers being returned by the spring independently of the said device.

fecting a relative approaching or separating movement between the wheel and the work support, a spring for pressing one of the centers against the blank, a spring associated with the other center and acting in the same direction as the first spring, and a device operable during grinding for moving the second center longitudinally in one direction in opposition to the springs independently of other parts of the work support, the blank and the centers being returned by the springs independently of the said device.

31. In combination in a cylindrical grinding machine, a rotatable grinding wheel, a work support provided with aligned centers for holding a work blank in operative relation to the wheel, means for rotating the work on the centers, feed mechanism for effecting a relative approaching or separating movement between the wheel and the work support, a spring for pressing one of the centers against the blank, and a manually operable cam rotatable about an axis perpendicular to the axis of the blank for moving the other center longitudinally in one direction in opposition to the spring independently of other parts of the work support.

32. The combination in a grinding machine, of a work support provided with devices for holding a work blank and formed with a guideway on its lower side, a grinding wheel rotatable about a fixed axis and having a broad face extending the full length of the part of the blank to be ground, feed mechanism for moving the work support toward or from the wheel, a wheel dressing tool, and a tool carrying slide movable along the said guideway.

33. The combination in a grinding machine, of a work support provided with devices for holding a work blank, a grinding wheel rotatable about a fixed axis and having a broad face extending the full length of the part of the blank to be ground, feed mechanism for effecting relative approaching and receding movements between the work support and the wheel, a wheel dressing tool, a tool carrying slide carried by and movable longitudinally of the work support, and power actuated mechanism carried in part by the work support for moving the slide.

34. The combination in a grinding machine, of a work support provided with devices for holding and rotating a work blank and mounted for pivotal movement about an axis parallel with the axis of the blank, a grinding wheel rotatable about a fixed axis parallel with the axis of the work blank and having a broad face extending the full length of the part of the blank to be ground, feed mechanism for swinging the work sup-

port about its pivotal axis toward or from the wheel, a wheel dressing tool, a tool carrying slide carried by and movable longitudinally of the work support, and power actuated mechanism for moving the slide carried in part by the work support and comprising a rotatable element having its axis coincident with the pivotal axis of the work support.

35. The combination in a grinding machine, of a work support provided with devices for holding a work blank and mounted for pivotal movement about an axis parallel with the axis of the blank, means at one end of the work support for rotating the blank, a grinding wheel rotatable about a fixed axis parallel with the axis of the work blank and having a broad face extending the full length of the part of the blank to be ground, feed mechanism for swinging the work support about its pivotal axis toward or from the wheel, a wheel dressing tool, a tool carrying slide carried by and movable longitudinally of the work support, a rotatable shaft having its axis coincident with the pivotal axis of the work support, a connection between one end of the shaft and the means for rotating the blank, and means connected with the other end of the shaft and carried by the work support for moving the tool carrying slide.

36. The combination in a grinding machine, of a work support provided with devices for holding a work blank, a grinding wheel rotatable about a fixed axis and having a broad face extending the full length of the part of the blank to be ground, feed mechanism for moving the work support toward or from the wheel, a wheel dressing tool, a tool carrying slide carried by and movable longitudinally of the work support, and power actuated mechanism carried in part by the work support for moving the slide optionally in either direction.

37. The combination in a grinding machine, of a work support provided with devices for holding a work blank, a grinding wheel rotatable about a fixed axis and having a broad face extending the full length of the part of the blank to be ground, feed mechanism for moving the work support toward or from the wheel, a wheel dressing tool, a tool carrying slide carried by and movable longitudinally of the work support, power actuated mechanism carried in part by the work support for moving the slide in either direction, and manually operable means for starting and stopping the power actuated mechanism.

38. The combination in a grinding machine, of a work support provided with devices for holding a work blank, a grinding wheel rotatable about a fixed axis and having a broad face extending the full length of

the part of the blank to be ground, feed mechanism for moving the work support toward or from the wheel, a wheel dressing tool, a tool carrying slide carried by and 5 movable longitudinally of the work support, power actuated mechanism carried in part by the work support for moving the slide in either direction, and means comprising a horizontal rod extending across the front of 10 the work support for starting and stopping the power actuated mechanism.

39. The combination in a grinding machine, of a work support provided with devices for holding a work blank, a grinding 15 wheel rotatable about a fixed axis and having a broad face extending the full length of the part of the blank to be ground, feed mechanism for moving the work support toward or from the wheel, a wheel dressing tool, a tool carrying slide carried by and 20 movable longitudinally of the work support, power actuated mechanism carried in part by the work support for moving the slide, and adjustable means for stopping the slide after 25 movement to a predetermined extent.

40. The combination in a grinding machine, of a work support provided with devices for holding a work blank, a grinding wheel rotatable about a fixed axis and having 30 a broad face extending the full length of the part of the blank to be ground, feed mechanism for moving the work support toward or from the wheel, a wheel dressing tool, a tool carrying slide carried by and movable 35 longitudinally of the work support, power actuated mechanism carried in part by the work support for moving the slide, and adjustable means for stopping the slide after movement to a predetermined extent in 40 either direction.

41. The combination in a grinding machine, of a work support provided with devices for holding a work blank, a grinding wheel rotatable about a fixed axis and having 45 a broad face extending the full length of the part of the blank to be ground, feed mechanism for moving the work support toward or from the wheel, a wheel dressing tool, a tool carrying slide carried by and movable longitudinally of the work support, power actuated mechanism carried in part by the work support for moving the slide, adjustable means for stopping the slide after movement to a predetermined extent, and means for manually releasing the slide to permit additional movement without changing the adjustment of the stopping means. 55

42. The combination in a grinding machine, of a work support provided with devices for holding a work blank, a grinding wheel rotatable about a fixed axis and having a broad face extending the full length of the part of the blank to be ground,

feed mechanism for moving the work support toward or from the wheel, a wheel dressing tool, a tool carrying slide carried by and movable longitudinally of the work support, power actuated mechanism carried in part by the work support for moving the slide, adjustable means for stopping the slide after movement to a predetermined extent, means for manually releasing the slide to permit additional movement without changing the adjustment of the stopping means, and a supplemental means for stopping the slide at a fixed point. 65 70 75

43. The combination in a grinding machine, of a work support provided with devices for holding a work blank, a grinding wheel rotatable about a fixed axis and having a broad face extending the full length of the part of the blank to be ground, feed mechanism for effecting relative approaching movement between the work support and the wheel, a wheel dressing tool, a tool carrying slide movable longitudinally of the wheel face, and a former for moving the tool toward and from the axis of the wheel during longitudinal movement. 80 85 90

44. The combination in a grinding machine, of a work support provided with devices for holding a work blank, a grinding wheel rotatable about a fixed axis and having a broad face extending the full length of the part of the blank to be ground, feed mechanism for moving the work support toward or from the wheel, a slide carried by and movable longitudinally of the work support, a second slide carried by and movable transversely of the first slide, a wheel dressing tool carried by the second slide, and a former for moving the second slide relatively to the work support toward and from the axis of the wheel during longitudinal movement of the first slide. 95 100 105

45. The combination in a grinding machine, of a work support provided with devices for holding a work blank, a grinding wheel rotatable about a fixed axis and having a broad face extending the full length of the part of the blank to be ground, feed mechanism for moving the work support toward or from the wheel, a slide carried by and movable longitudinally of the work support, a wheel dressing tool carried by the slide and movable relatively to the slide toward and from the axis of the wheel, a spring for moving the tool toward the wheel axis, and a former for limiting the movement of the tool under the action of the spring and for guiding it to dress the wheel to a predetermined contour. 110 115 120

46. The combination in a grinding machine, of a work support provided with devices for holding a work blank, a grinding wheel rotatable about a fixed axis and having a broad face extending the full length

of the part of the blank to be ground, feed mechanism for moving the work support toward or from the wheel, a wheel dressing tool, a tool carrying slide carried by and 5 movable longitudinally of the work support, a former for moving the tool toward and from the axis of the wheel during longitudi- nal movement, and power actuated mechanism carried in part by the work support for moving the slide. ¹⁰

In testimony whereof, I hereto affix my signature.

BENGT M. W. HANSON.
